Honolulu.

UNITED STATES PATENT OFFICE.

VICTOR MAUCK, OF NORRISTOWN, PENNSYLVANIA.

MUNITION CASING.

1,427,220.

Specification of Letters Patent. Patented Aug. 29, 1922.

Application filed February 28, 1918. Serial No. 219,674.

To all whom it may concern:

Be it known that I, VICTOR MAUCK, a citizen of the United States, residing at Norristown in the county of Montgomery and

5 State of Pennsylvania, have invented a certain new and useful Improvement in Munition Casings, whereof the following is a specification, reference being had to the accompanying drawing.

10 The present invention is a modification of the invention described in my application Serial 217,037, filed February 14, 1918, for Letters Patent of the United States, having as its object to provide a casing which may 15 be hermetically sealed for the transportation of explosives but which may not only be readily opened to discharge its contents, but may be resealed, so that the casing can be again used for the same purpose, as distinguished from ordinary munition casings which are provided with sealing means which are destroyed when the casing is opened.

As it is of the utmost importance, in the 25 present state of war, to minimize the weight of all containers used in the transportation of munitions; it is one object of my invention to provide a suitable removable closure for a munition casing, which closure may be 30 made of thin pressed sheet metal, and, consequently, is far less weighty than if made of cast metal of the same strength.

The form of my invention hereinafter described comprises means for interlocking a 35 munition casing with a removable closure so that the latter cannot be accidentally displaced, and includes the provision upon the munition casing of a flange which presents a downwardly turned ledge, to afford the 40 maximum security of engagement of the hooks which hold the closure upon the casing; and simplified means for pivotally supporting the closure hooks without the use of pivot pins as shown in the drawing, and 45 hereinafter described, said downwardly turned ledge is preferably formed by a flange which is in unitary relation with the munition casing; that is to say, the same sheet of metal is used to form the tubular 50 body of said casing and said flange, as distinguished from certain structures of the prior art in which casings are provided with primarily separate flange rings, to engage means for securing the casing closure. Moreover, a convenient adjunctive feature of my 55 invention is the provision of means to seal

the screw by which the closure is held on the casing, so that the casing cannot be opened without breaking said seal and thus indicating the fact that it has been opened. 60

My invention includes the various novel features of construction and arrangement hereinafter more definitely specified.

In the drawing; Fig. I is a plan view of a munition casing embodying a convenient 65 form of my invention.

Fig. II is a longitudinal sectional view of said casing, taken on the line II, II in Fig. I.

Fig. III is an inverted plan view of said 70 casing.

Fig. IV is a perspective view of one of the spider yoke arms.

Fig. V is a perspective view of the pivoted hook latch shown in Figs: I and II, which 75 is adapted to fit in the slot of the yoke arm shown in Fig. IV.

In said figures; the body of the munition casing is a cylindrical tubular shell. Said shell is preferably formed of a primarily 80 plane sheet of commercial steel electrically welded at a single longitudinal seam 2, and permanently closed by the bottom plate 3,

having the cylindrical flange 4 united to said shell 1 by an oxy-acetylene welding 85 process. The opposite, upper, end of said shell 1 is preferably provided with an integral outwardly turned flange 6 of semi-circular cross section, which affords a bearing for the gasket 7 which may be of rubber or other suitable material. The closure 90 for said casing includes the lid 9 which is a saucer-shaped circular plate of pressed sheet metal, having an annular flange 10 complementary to and arranged to interlock 95 with said casing flange 6 and to bear upon said gasket 7. The spider frame or yoke 12 is also preferably formed of pressed sheet metal, with three arms of U-shaped cross section overhanging said lid 9, and each having a hook adapted to engage under said casing flange 6, as shown in Fig. II. The two hooks 13 are bendable but preferably integral with said yoke. The hook 14 is a latch, conveniently formed of stamped, 100 primarily flat, sheet metal, having its upper end 15 bent downwardly through the slot 16 in the outer end of the arm 17 of said yoke 12.

The nut 19, which is preferably a standard size hexagon nut, is permanently secured in said yoke 12, conveniently by in-

wardly bent lugs 20 on said yoke. The set screw 21 which extends in said nut 19, in engagement with said lid 9, is conveniently provided with the T head 22, or other suitable wrench hold exterior to said yoke. Said T head has the hole 23 to receive the seal wire 25 which also extends through the holes 26 in said yoke arm 17, and has its ends twisted together and imbedded in the seal 27, 10 conveniently formed of lead or other soft metal; said wire and seal being employed to indicate whether the casing has remained unopened during its transportation.

It is to be understood that in the position shown in Fig. II, said casing 1 is hermetically sealed by pressure of said screw 21 upon said lid 9, compressing said gasket 7 at the joint between said casing flange 6 and the flange 10 of said lid; thus 20 preventing access of air and moisture to the explosive material 28 in said casing. However, said screw 21 may be turned, by the wrench hold 22, until its pressure upon said lid 9 is relieved; whereupon, said 25 latch 14 may be rocked on its pivotal connection to said yoke arm 17, to disengage its hooked end from beneath said casing flange 6; thus enabling the operator to withdraw the yoke 12 and remove said lid 9, 30 without damaging said casing 1, and thus permitting its repeated use.

Said flange 6, being formed, as shown in Fig. II, in unitary relation with the wall of the shell 1, is not only less costly than 35 a ledge formed by a primarily separate ring, as in structures of the prior art, but, having a hollow beneath it, is adapted to receive the upwardly extending end of the hook 14 and more securely engage the closure, in 40 the position shown in Fig. II, than if said flange were not thus formed. The saucer shape of the lid 9, (best shown in Fig. II) is advantageous in that the point of engagement between the set screw 21 in said 45 lid is nearer to the bottom of the casing than the seat for the lid upon said flange 6 and I thus utilize the tensile strength of the metal of said lid, in maintaining uniformity and stability of engagement of the 50 lid upon said flange 6, throughout its circumference. The fact that said shell 1, lid 9, and the yoke 12 are distinct and separate entities is advantageous in that if any one

is damaged, another may be instantly substituted, whereas, if they were permanently 55 connected, damage to any one of them would render the entire group useless until the damaged member could be repaired and, as such damages are frequently incurred by reason of the rough usage to 60 which munition casings are necessarily subjected, such separable relation of said elements is important in the maintainance of the maximum number of casings in service.

It may be observed that such casings as 65 above described are adapted to stably stack in vertical alinement; the recessed bottom of one casing being supported by the arms of the yoke of the subjacent casing, said recessed bottom affording clearance for the 70 central screw of the subjacent casing.

Of course, such closures as above described may be used on casings differing from the casing 1. Therefore, I do not desire to limit myself to the precise details of construction and arrangement herein set forth, as it is obvious that various modifications may be made therein, without departing from the essential features of my invention as defined in the appended claims. 80

I claim:

1. In a munition casing, the combination with a tubular shell; of a closure for said shell including a lid, a rigid yoke having arms overhanging said lid, with hooks at 85 their outer ends, one of said arms having a slot extending through it, and its hook pivotally engaged in said slot; all of said hooks being adapted to directly detachably engage said shell. 90

2. A vessel closure yoke formed of pressed sheet metal, including a plurality of arms each having a hook at its outer end; one of said hooks being pivotally engaged in a slot in its arm, and means on the latter arm 95 limiting the movement of said hook toward said closure.

In testimony whereof, I have hereunto signed my name at Norristown, Pennsylvania, this twenty-sixth day of February, 100 1918.

VICTOR MAUCK.
